United States Patent Office.

JAMES F. VALENTINE, OF UNION COUNTY, OHIO.

Letters Patent No. 65,845, dated June 18, 1867.

IMPROVED MODE FOR DRESSING SIDE STRAPS FOR HARNESS.

The Schedule referred to in these Letters Patent and making part of the same.

TO ALL WHOM IT MAY CONCERN:

Be it known that I, JAMES F. VALENTINE, of Union county, and State of Ohio, have invented a new and useful Machine for Dressing Tugs or Side Straps of Harness; and I do hereby say that the following is a full, clear, and exact description of the construction and operation of the same, reference being had to the annexed drawings, making a part of this specification, in which—

Figure 1 is a longitudinal central section; and

Figure 2, a plan or top view of the same.

The strap to be dressed is placed within the box, which is adjusted to the same by the means of the screws *d d*. The levers *b b* are to be let fall on strap, and secured by means of the screws *e e*. The pin or bolt *c* holds the strap level while it is being drawn between the knives or blades *f f*, which dress the strap or tug as it passes through.

To enable others skilled in the art to make and use my invention, I will proceed to describe its construction and operation.

By means of the screws *d d* the box or trough is made to widen, so as to accommodate any width of tug or strap needed to be dressed. The tug or strap is then placed in box, and by turning the large screws the desired width is properly adjusted. The levers *b b* are then let down on the leather, and secured by the screws (small) *e e* on the sides of the box. The pin or bolt *c* is then placed in position over the tug or strap, which is thus held level as it comes against the knives *f f*.

What I claim as my invention, and desire to secure by Letters Patent, is—

The combination and arrangement of the knives or bits *f f* with the box or trough, together with the levers *b b*, the pin or bolt *c*, and the widening or regulating screws *d d*, substantially as set forth and for the purpose therein named.

JAMES F. VALENTINE.
